UNITED STATES PATENT OFFICE.

EUGENE EMMETT MASON, OF ATLANTA, GEORGIA.

STOVE.

Application filed October 18, 1921. Serial No. 508,455.

To all whom it may concern:

Be it known that I, EUGENE E. MASON, a citizen of the United States, residing at Atlanta, in the county of Fulton and State of Georgia, have invented new and useful Improvements in Stoves, of which the following is a specification.

This invention relates to improvements in stoves, the general object of the invention being to eliminate the dampers in the stove so as to obviate damper trouble, such as the burning out of the same and to improve the heating qualities of the stove.

Another object of the invention is to cause the heat to pass under practically the whole stove top, both when the oven is being used and when it is not being used.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a front view of a stove constructed in accordance with my invention with parts in section.

Figure 2 is a section on line 2—2 of Figure 1.

Figure 3 is a section on line 3—3 of Figure 2.

Figure 4 is a rear view.

Figure 5 is a view of the damper 13.

Figure 6 is a section on line 6—6 of Figure 3.

In these views 1 indicates the casing of the stove which is provided with the usual fire box 2, ash pit 3 and oven 4, the oven being formed of the sheet 5 which forms a partition between the oven and firebox, and the top and bottom sheets 6 and 7 and the end sheet 8. The top and bottom sheets and the end sheet form a flue or passage 9 for the products of combustion which after flowing around the oven pass into the flue 10 at the rear of the stove from which they

pass into the pipe 11 and thus pass to the chimney. I form a horizontal flue 12 at the rear of the stove which connects the pipe 11 with the rear upper part of the vertical portion of the flue or passage by the opening 10' and the connection of this flue with the pipe is controlled by a damper 13. When this damper is in position closing the flue 12 the products of combustion must pass around the oven but when this damper is open the products of combustion will pass over the oven and through flue 12 into the pipe. Thus in both cases the products of combustion will come in contact with practically the entire stove top instead of only coming in contact with a portion thereof when the damper opening is placed at the center of the stove as at present. My arrangement of parts also places the damper where the products of combustion are not so hot so that there is no danger of burning out the damper parts as at present.

Attention is called to the fact that my stove does not contain a damper or damper strip at all and that the direct and indirect draft is controlled by a single damper in the pipe above the stove. Thus my stove can be manufactured more quickly and with less expense than stoves containing dampers and the danger of burning out dampers is eliminated. My damper is always turned from the heat so that it is almost impossible to burn it.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A stove of the class described comprising an oven spaced from the body of the stove to form horizontal flues and a vertical flue which connects the two horizontal flues together, one horizontal flue being arranged above the oven and the other below the oven, a chimney flue connected with the lower horizontal flue adjacent its closed end, a horizontal flue at the top of the stove at the

rear thereof, the rear of the stove having an opening therein which is located at the junction of the vertical flue with the upper horizontal flue and connects these flues with the chimney and a damper in said connecting pipe for controlling communication thereof with the rear horizontal flue and **10** with the chimney flue.

5 the horizontal flue at the rear of the stove, a pipe on the top of the stove for connecting the rear flue and the chimney flue with

In testimony whereof I affix my signature.

EUGENE EMMETT MASON.
